UNITED STATES PATENT OFFICE.

JAMES P. GATES, OF MILWAUKEE, WISCONSIN, ASSIGNOR OF ONE-HALF TO JOHN GLISCH,
OF MILWAUKEE, WISCONSIN.

TOBACCO-MOISTENER.

No. 881,790.

Specification of Letters Patent. Patented March 10, 1908.

Application filed June 20, 1907. Serial No. 379,833.

To all whom it may concern:

Be it known that I, JAMES P. GATES, a citizen of the United States, residing at Milwaukee, county of Milwaukee, and State of 5 Wisconsin, have invented new and useful Improvements in Tobacco-Moisteners, of which the following is a specification.

My invention relates to improvements in tobacco moisteners.

10 The object of my invention is to provide a small removable receptacle composed of non-corrosive material perforated on opposite sides and filled with a body of absorbent material which is not subject to decay, the receptacle being capable of being loosely deposited in a tobacco pouch or box where it will be moved from one point to another in the act of removing tobacco or cigars from the pouch or box and the tobacco thus kept 15 sufficiently moist to prevent deterioration.

In the following description reference is had to the accompanying drawings, in which,

Figure 1 is a plan view of my invention. Fig. 2 an edge view of the same, and Fig. 3 a 25 sectional view.

Like parts are identified by the same reference characters throughout the several views.

A receptacle, preferably circular in form, is provided with a perforated top A and bottom B, the side walls being curved inwardly and lapped upon each other in the form of a circular bead C, the meeting walls being pressed together so as to permanently unite the top and bottom portions. Within the 35 receptacle is located a body of absorbent material D, preferably asbestos or mineral wool, which may be permitted to project in light feathery strings E from the apertures F in the top and bottom walls and whereby the 40 moisture carried by the body of asbestos within the receptacle will be distributed, not only by evaporation through perforations, but by capillary attraction. The top and bottom walls are preferably made substantially flat 45 as shown and have rounded margins presenting no sharp edges which might otherwise damage the wrappers of cigars.

The receptacle when dried is dropped into a basin of water which readily penetrates the 50 absorbent material by reason of the fact that there are perforations in both the top and bottom walls. When filled with water, the receptacle is removed and placed in the tobacco box or pouch. The provision of the

perforations in both the top and bottom walls 55 not only facilitates entry of water into the receptacle but also facilitates evaporation as a slight circulation of air is possible through the receptacle.

When freshly filled with water, the receptacle may be placed on edge as illustrated in Fig. 2 and as the rounded sides are imperforate, any surplus water in the receptacle will settle into the imperforate margin and will not pass through the perforations in the 60 top and bottom walls. As the cigars are removed from the box, however, the receptacle will be shifted to different parts thereof and will be turned on its side, thus distributing 65 the moisture.

I attach great importance to the fact that the receptacle is unattached and free to move from side to side, since a fixed receptacle tends to produce excessive moisture in one portion of the box, especially if in actual or 70 approximate contact with the cigars or tobacco, it being well known that tobacco absorbs moisture with great facility.

I also consider it important that the receptacle should be formed of non-corrosive 75 light material such as aluminium, that its outer surface be smooth with no square corners or projections which could injure the wrappers of the cigars, and that the absorbent material shall be such as will not decay, — 80 asbestos fiber being preferred.

Having thus described my invention what I claim as new and desire to secure by Letters Patent is,

1. A tobacco moistener comprising a 85 loose unattached receptacle having substantially flat top and bottom walls and imperforate rounded sides interlocking with each other to form a permanently closed receptacle, said top and bottom walls being 90 perforated and said receptacle containing a body of absorbent material not subject to decay, such as asbestos or mineral wool.

2. A tobacco moistener comprising a 100 loose unconnected receptacle having substantially flat top and bottom walls and with a smooth surface and without corners or projections rounded sides interlocking with each other to form a permanently closed receptacle, said top and bottom walls being 105 perforated and said receptacle containing a body of absorbent material not subject to decay, such as asbestos or mineral wool, the

absorbent material being permitted to extend in light feathery strings through some of the openings, whereby the moisture carried by said material is distributed both by evaporation through the perforations and by capillary attracting and by evaporation from the outwardly projecting portions.

In testimony whereof I affix my signature in the presence of two witnesses.

JAMES P. GATES.
